Specification for Design.

Patented Nov. 16, 1909.

Application filed April 29, 1909. Serial No. 493,046. Term of patent 14 years.

To all whom it may concern:

Be it known that I, WILLIAM L. SERGEANT, a citizen of the United States, residing at Nutley, in the county of Essex and State of New Jersey, have invented a new, original, and ornamental Design for Safety-Paper, of which the following is a specification, reference being had to the accompanying drawing, forming part hereof.

The drawing illustrates the design as nearly as it can be shown by black lines on

one side of a white ground. The actual design however consists of the pattern shown by said drawing on both sides of the paper, and as appearing in the body of the same.

I claim—

The ornamental design for safety paper, as shown and described.

WILLIAM L. SERGEANT.
